(No Model.)

H. KLAHRE.
GAS AND AIR MIXER.

No. 414,549.

Patented Nov. 5, 1889.

UNITED STATES PATENT OFFICE.

HERMANN KLAIRE, OF CHICAGO, ILLINOIS.

GAS AND AIR MIXER.

SPECIFICATION forming part of Letters Patent No. 414,549, dated November 5, 1889.

Application filed February 26, 1889. Serial No. 301,197. (No model.)

To all whom it may concern:

Be it known that I, HERMANN KLAIRE, a resident of Chicago, in the county of Cook and State of Illinois, have invented certain new and useful Improvements in Gas and Air Mixers, of which the following is hereby declared to be a full, clear, and exact description, sufficient to enable others skilled in the art to which such invention relates to make and use the same.

The invention relates to gas-holders of the usual type comprising an open inverted drum submerged within an inclosing water-tank; and such invention consists of certain improvements in structure whereby the holder receives air and gas in separate chambers of the drum and discharges the same suitably mixed into a carburetor of any approved pattern, wherein the mixed air and gas are enriched with gasoline or other vapor preparatory to burning for illumination.

The invention designs to control the admission of air and gas to the holder automatically under conditions dependent upon the consumption of the carbureted gas and air and the consequent falling of the inverted drum within its water-tank.

The nature of the improvements will fully appear from the description following, and be thereafter more distinctly pointed out in the claims at the conclusion thereof.

In the accompanying drawings, forming part of this specification, like letters of reference denote like parts of structure throughout.

Figure 1 is a view of the improved holder in longitudinal section on line 1 1 of Fig. 3. Fig. 2 is a like view on line 2 2 of Fig. 1. Fig. 3 is a view in cross-section on line 3 3 of Fig. 1. Fig. 4 is a detail section view of the gas-inlet valve.

Mounted within the submerging water-tank A, of ordinary construction, is the open inverted drum B, having its lower end to dip within the water in tank A for the purpose of effecting a seal, as well understood. The space within the drum B above the water seal constitutes a chamber for the air, and there is also a supplemental chamber for the gas, which in the form shown by the drawings is made by securing a dependent cylinder b to the top of the drum B, such inner cylin-

der being of comparatively small diameter and extending downwardly for about the depth of the drum. An inlet-pipe a extends through the side of the tank A and opens 55 into the annular space or chamber of the drum B external to the cylinder b. The pipe a at its outer end terminates in a goose-neck to suitably receive and seat the ball-valve c, and at its inner end said pipe a is furnished 60 with a proper cage to receive the ball-valve d. The one-way valves c d open inwardly to permit the free admission of the air to the drum B during the upward movement of such drum. When, however, the drum descends, 65 the valves c d close against their seats and check the exit of air through the pipe a. Except for greater certainty in preventing the reflux of air through the pipe a, but one of such valves c d need be employed, and it is 70 obvious, also, that any other form of valve moving lightly to and from its seat may be substituted in place of the ball-valves c d.

The gas-induct pipe passes through the wall of the tank A and opens within the inner cylinder b above the water seal. The pipe e communicates externally with any suitable source of gas-supply—such, for example, as produces hydrogen gas by action of sulphuric acid upon zinc or iron filings or the like. At 80 its inner terminal said pipe e is furnished with a one-way valve f, which, as in the form shown, may conveniently be of the piston type, having a stem g, which extends upwardly into the trip or shifting case h, fastened to the under side of the top of the drum B. The valve f closes against the seat, as at i, secured to the end of the pipe e, and is preferably furnished with spring-fingers k, which bear against the stem g of the valve 85 and guide the latter firmly to its seat. The spring-fingers k serve also to retain the valve f in closed position during the descent of the drum B until the head l of the valve-stem g is struck by the top of the drum B. During 90 the upward movement of the drum the head l of the valve-stem g finally engages with the inturned lugs of the trip h, which thereby lift the valve f against its seat i and check the further admission of gas to the holder.

The eduction-pipes m n, leading, respectively, from the air and gas chambers of the

holder, are preferably furnished with goose-neck terminals having ball-valves *o p* therein, and said pipes discharge into a common delivery-pipe *q*, which extends thence to the 5 carburetor of any suitable pattern.

Instead of the ball-valves *o p* the eduction-pipes *m n* may be furnished with any other type of light-moving one-way valve, or such valves may be entirely dispensed with, and 10 a single one-way valve be employed, located, as shown in dotted lines, in the common delivery-pipe *q*. Since the inner ends of the pipes *m n* are above the line of water seal of the gas-holder, the air and gas within the 15 chambers of the holder on release of pressure at the carburetor or beyond lightly lift the valves *o p* and become freely mixed in the delivery-pipe *q*, passing thence to the carburetor to be enriched.

20 Instead of attaching the pipes *m n* to each other by a T-joint within the tank A, it is manifest that these may be so joined beyond the tank or be connected with a common delivery-pipe discharging into the carburetor.

25 According to the invention detailed gas and air in proper volumes will be admitted into the holder until the same is filled, when the further supply will be checked automatically by the closing of the gas-valve *f* against its 30 seat. Thereafter as the gas and air are withdrawn and mixed these will pass from the holder by the delivery-pipe *q* only, any tendency to reflux being checked by the one-way valves *c d* in the induct-pipe *a* and by the 35 valve *f* in the induct-pipe *e*, respectively. The one-way valves *o p*, or the single valve in delivery-pipe *q*, as the case may be, will check the reflux of the mixed air and gas through the pipes *m n* during the time that 40 the drum B is ascending and is being filled through the pipes *a e*.

Obviously the details of the construction hereinbefore set forth may be varied, within the skill of the mechanic to effect them, without departing from the spirit of the invention, which, consequently, is not limited to such details.

Having thus described the invention, what I claim as new, and desire to secure by Letters Patent, is—

1. The combination, with the holder having separate air and gas chambers, and with the induct and educt pipes severally leading to and from each of said chambers, of the one-way inlet-valves singly for said induct-pipes 55 and the one-way outlet-valves (or valve) singly for said educt-pipes, respectively, the inlet-valve for the gas-induct pipe being controlled automatically by movement of the inverted drum of the holder, while the outlet-pipes are free to discharge on release of pressure beyond their valves (or valve) irrespective of the position or shift of such holder, substantially as described.

2. The combination, with the inverted drum 65 of the holder having separate air and gas chambers, of the induct-pipes opening severally into said chambers, the one-way inlet-valves for said pipes, (the gas-inlet valve being furnished with an extended stem which coacts 70 with a trip from said drum,) and the educt-pipes leading severally from said chambers, such pipes having inner goose-neck terminals with ball-valves therein, whereby said outlet-pipes are free to discharge on release 75 of pressure beyond the valves irrespective of the position or shift of said holder, substantially as described.

3. The combination, with the gas-holder having the usual inverted drum, of an induct-pipe, a one-way inlet-valve mounted thereon and furnished with an extended stem, and a trip projecting inwardly within said drum to engage such stem and shift the valve, substantially as described.

4. In gas-holders, the combination, with the inverted drum and the inlet-pipe therefor having a valve-seat *i* and spring-fingers *k* extending therefrom, of the valve *f*, bearing against said seat, the stem *j*, projecting from 90 said valve within the clasp of the spring-fingers and having a cross-head terminal *l*, and the trip *h*, carried by the drum and having inturned lugs to coact with said cross-head, substantially as described.

HERMANN KLAIRE.
